UNITED STATES PATENT OFFICE

JEWEL CARMEN WEST, OF LOS ANGELES, CALIFORNIA

BRASSIÈRE

Application filed June 1, 1928. Serial No. 112,786.

This invention relates to a brassière, and the general object of the invention is to provide a construction for a brassière which will be comfortable when worn and which is so 5 constructed as to enable it to be readily worn with a low-neck gown.

One of the objects of the invention is to provide a construction which will be devoid of a connection with the waist band at the 10 front, thereby avoiding discomfort from a pulling effect over the shoulders which sometimes is present in brassières.

A further object of the invention is to provide an improved construction for the girdle 15 of the brassière which will enable it to be given shape from a few pieces of material and in a simple manner.

Further objects of the invention will appear hereinafter.

20 The invention consists in the novel parts and combination of parts to be described hereinafter, all of which contribute to produce an efficient brassière.

A preferred embodiment of the invention 25 is described in the following specification, while the broad scope of the invention is pointed out in the appended claims.

In the drawing:

Figure 1 is a perspective illustrating the 30 appearance of the brassière from the front, when being worn.

Figure 2 is a perspective showing the brassière from the rear.

Figure 3 is a perspective showing a side 35 view of the brassière.

Figure 4 is a plan illustrating a portion or piece of material from which the girdle can be readily constructed at the front.

Figure 5 is a view similar to Fig. 4, but 40 showing a lower portion or piece which cooperates with the piece shown in Fig. 4 to give the girdle the desired shape at the front.

Figure 6 is a plan showing the piece which completes the girdle at each side, and through 45 which the same may be connected to the shoulder straps at the back.

In practicing the invention, I provide a pair of shoulder straps 1 which are secured in some way at the back, such as at the point 50 2 (see Fig. 2). These straps are preferably

connected together at the point where they are secured. If desired, they may be secured to the waist band of an underskirt, but I prefer to provide a waist band 3 which forms a part of the brassière. This waist band is 55 "floating" and unconnected to any other part at the front of the body and may be constructed in any suitable way to enable it to be applied to the waist of the wearer, but I prefer to construct it as an endless elastic band or belt that extends continuously across the back.

The shoulder straps 1 diverge from each other from the anchorage point 2 upwardly, and extend over the shoulders 4 so as to give the shape at the back of a large V. The forward ends 5 of the shoulder straps 1 simply hang down over the shoulders at the front, and these ends 5 support the girdle or body 6 of the brassière. This girdle extends across 70 the bosom and passes around to the back. It is "floating" at the sides, that is, it is devoid of attachments and extends around to the back in a downward direction, and is attached to the shoulder straps at the back 75 near their point of attachment to the waistband, as will now be described. In order to facilitate the adjustment of the brassière to the body, one end of the girdle is permanently secured to one of the straps 1 at the point 7 (see Fig. 2), and the other end of the girdle is provided with button holes 8 to receive buttons 9 carried by the opposite shoulder strap. While I have illustrated button holes and buttons as used for making this connection, obviously snap fasteners or pins or any other desired means may be employed for this purpose.

By attaching the ends of the girdle to the shoulder straps 1 near their point of attachment 90 2 to the waistband 3, the rear portion of the girdle can perform the function of holding the lower portions of the straps at the back, displaced toward the side, away from a straight line joining the attaching point 2 and the shoulder. This is most advantageous as it insures that the straps cannot be seen with a dress which is quite low in the back and of V-form.

The girdle or body of the brassière is pref- 100

erably constructed of an upper band 10 and a lower band 11, said bands being of narrow width at the middle in front and being of greater width toward the sides. If desired, the upper band may be constructed of two parts or pieces 10^a (see Fig. 4), and the lower band may be constructed of two pieces 11^a (see Fig. 5). In constructing the upper band, two pieces shaped as the piece 10^a are connected together at their edges 12 to form the upper part of a front seam 13 of the brassière. Likewise the edges 14 of the pieces 11^a are connected together so as to form the lower portion of this front seam 13. The edges 15 and 16 of the pieces 10^a and 11^a are then overlapped and secured together to produce a horizontal middle seam 17 which extends across the front of the brassière. By reason of the increased width of the pieces 10^a and 11^a toward the sides, the brassière 20 will be given the desired shape.

The edges 18 and 19 of the pieces 10^a and 11^a are connected together in alignment and they are secured to an edge 20 of a back piece 21, illustrated in Fig. 6. There are two of these back pieces 21, the forward ends of which are attached to the corresponding side or end of the girdle, and they complete the girdle by extending around to the back where they are attached to the shoulder straps, as already described. If desired, the upper and lower edges of the girdle may be formed with hems 22 which finish off and strengthen the edges of the girdle.

The girdle of course may be constructed of any desired material, but it is preferably constructed of a light material such as net. When net is used for this purpose, the free end of the girdle, which is attached by means of the buttons 9, is preferably provided with a reinforcing piece 23 of light cloth or similar material.

When a brassière having these features of construction is worn, it does not restrict the movements of the body in any way, and by reason of the fact that the girdle is unconnected with the waist band 3 at the front, the wearer of the brassière never experiences any pulling effect of the shoulder straps upon the shoulders. Furthermore, the brassière is left open between the shoulder straps 1 to a point near the waist band, which enables the garment to be worn with a gown having quite a low cut in the back.

As indicated in Figure 2, the points of attachment of the girdle to the shoulder straps 1 are considerably above the waist band 3 toward the arm pits and this has the effect of maintaining the shoulder straps well out toward the points of the shoulders. This enables the brassière to be worn with a low-necked dress without exposing the shoulder straps.

The shoulder straps are preferably constructed of elastic material.

What I claim is:—

1. A brassière consisting of the combination of a pair of shoulder straps, a narrow waistband in the form of a belt floating and unconnected to any part at the front, extending continuously around the waist and secured to the shoulder-straps at the back, said shoulder-straps being disposed apart and leaving an unobstructed wide V-shaped area on the wearer's back, extending from the wearer's waistline to the shoulder, and extending over and hanging from the shoulders at the front, and a girdle having relatively wide portions in line respectively with the right and left breast, supported at the front on said shoulder-strap, said girdle floating at the sides and extending toward the back in a downward direction under the arms, terminating at the back at the adjacent shoulder straps respectively and held in place solely by the shoulder-straps at the front, said girdle being secured to the shoulder-straps at the back near their point of attachment to the waistband. 70 75 80 85

2. A brassière consisting of the combination of a pair of shoulder-straps disposed in the form of a large V at the back, a waistband in the form of an elastic belt floating and unconnected to any part at the front and sides and extending continuously across the back and secured at the waistline of the wearer to the shoulder-straps at the back, said straps extending over and hanging from the shoulders at the front, a girdle having relatively wide portions in line respectively with the right and left breast attached to the shoulder-straps at the front and held in place at the front solely by the shoulder-straps, said girdle extending around to the back in a downward direction at the sides and terminating at, and secured to, the shoulder-straps at the back and operating to hold each shoulder-strap displaced laterally outwardly and away from a straight line extending from the shoulder to the point of attachment of the strap and waistband, said parts cooperating to leave an unobstructed V-shaped area on the wearer's back extending from the wearer's waistline to the shoulders. 90 95 100 105 110

3. A brassière consisting of the combination of a narrow waistband in the form of a belt extending around the waist and continuously across the back, said waistband being floating and unattached to any part at the front and sides and confined at the back to the location of the wearer's waistline, a pair of shoulder-straps secured to the waistband adjacent the middle of the waistband at the waistline of the wearer at the back, and forming a V so that said straps diverge from each other in an upward direction passing over and hanging from the shoulders at the front, and a girdle independent of, and unattached to, the waistband, floating at the sides, attached to and supported at the front on the 115 120 125 130

said shoulder-straps and extending around to the back in a downward direction at the sides terminating at and secured to, the shoulder-straps at the back near their point of attachment to the waistband, said parts co-operating to leave an unobstructed V-shaped area on the wearer's back extending from the wearer's waistline to the shoulders.

Signed at Los Angeles, California, this
10 14 day of May, 1926.
